SHOE FINISHER MACHINE

George C. Bennett, Huntsville, Ala.

Application May 29, 1939, Serial No. 276,423

6 Claims. (Cl. 12—1)

The invention relates to a shoe finisher machine and more especially to shoe repairing machinery.

The primary object of the invention is the provision of a machine of this character wherein the working tools of varying types are supported in a turret susceptible of adjustment so that a selected tool can be brought into use in a convenient manner on the adjustment of said turret.

Another object of the invention is the provision of a machine of this character wherein the selected tool for use when brought into position for the operation thereof effects passiveness in the other tools as supported by a turret, this being brought about on the adjustment of the turret and in this way eliminating the necessity for the driving of all of the tools on the turret when it is required that but one be in use.

A further object of the invention is the provision of a machine of this character wherein on the bringing of a selected tool into use will serve to automatically render the other tools inactive, that is to say, the tool for use will be in a convenient position for service and those tools remote from the operator of the machine will be out of the way and passive or inactive.

A still further object of the invention is the provision of a machine of this character, wherein footwear can be repaired with dispatch and such footwear finished to have the appearance of a new shoe or the like, the machine being also useable for the making of new footwear in that the soles and heels can be trimmed and finishing surfaces thereof had.

A still further object of the invention is the provision of a machine of this character, wherein the construction thereof in its entirety is novel and any desirable tool may be brought into position for use with dispatch while the remaining other tools in the set up of the machine will be maintained inactive and in this way saving power in the operation of the machine.

A still further object of the invention is the provision of a machine of this character which is comparatively simple in its construction, thoroughly reliable and efficacious in operation, easily handled enabling tools to be individually selected with dispatch for service thereof, and inexpensive to manufacture.

With these and other objects in view, the invention consists in the features of construction, combination and arrangement of parts as will be hereinafter more fully described in detail, illustrated in the accompanying drawings, which disclose the preferred and modified forms of the

embodiment of the invention and pointed out in the claims hereunto appended.

In the accompanying drawings:

Figure 1 is a side elevation of a machine constructed in accordance with the invention. 5

Figure 2 is an end elevation partly in section.

Figure 3 is a view similar to Figure 2 showing in elevation the other end of the machine.

Figure 4 is a horizontal sectional view through the machine taken longitudinally thereof. 10

Figure 5 is a top plan view partly in section.

Figure 6 is a sectional view taken approximately on the line 6—6 of Figure 5 looking in the direction of the arrows.

Figure 7 is a sectional view transversely of the 15 machine showing partly in elevation and partly in section the shields for the driving and driven parts thereof.

Figure 8 is a vertical longitudinal sectional view through a sole or heel trimming tool used with 20 the machine.

Figure 9 is an end elevation thereof.

Figure 10 is a perspective view of the cutter employed for sole or heel trimming.

Figure 11 is a fragmentary elevation partly in 25 section of a sanding wheel or disc employed in the machine.

Figure 12 is a fragmentary horizontal sectional view therethrough.

Figure 13 is a fragmentary sectional view 30 through the shields for the driving and driven connections of the machine.

Figure 14 is a fragmentary transverse sectional view showing in side elevation a modification of the invention. 35

Figure 15 is a fragmentary top plan view of the modification.

Figure 16 is a fragmentary horizontal sectional view through one of the belt tightener elements of the machine involved in the modified form. 40

Similar reference characters indicate corresponding parts throughout the several views in the drawings.

Referring to the drawings in detail, particularly Figures 1 to 12 inclusive, the machine comprises a stand A including vertically disposed end pieces 10 and 11, respectively, these being spaced from each other and constitute the legs to the said stand. At the upper portions of these pieces 10 and 11 are circular bearings 12 and 13 respectively. Within the bearing 13 is arranged an eccentric mounting 14 supporting an electric motor unit 15 being the power unit of the machine. The driving shaft 16 of the motor unit 15 has coupling at 17 with a driven shaft 18 50 55

operating a suction fan 19 of the bladed type held within a housing or casing 20 stationarily built with the stand A.

The fan 19 of the bladed type is driven directly 5 from the motor unit 15 through the medium of the shaft 18 and this coupling at 17 involves a double universal joint setup. Opening into the housing or casing 20 is a cylindrical conduit 21 for collection and delivery of dust or foreign matter to within the said housing or casing on 10 the operation of the said fan, the dust or foreign matter being taken from the work when operated upon by a tool of the machine, these being hereinafter described. This conduit 21 is coupled 15 with a central inlet nipple 21' formed with the housing or casing 20, the conduit 21 being rotatable and constitutes a part of a turret herein-after fully described.

The conduit 21 is centered within a tool turret 20 and has the shaft 18 longitudinally centered therein, the coupling 17 being for the purpose of transferring power from the shaft 16 to the shaft 18 in the operation of the motor unit 15. Turnable about the bearing 13 and the nipple 21' is 25 the tool turret comprising rotatable end heads 22 and 23, respectively. The head 23 is rotatable on the bearing 13 while the head 22 rotates on the nipple 21'. Concentric to this conduit 21 and journaled in the said heads 22 and 23 are 30 opposed driven shafts 24, these being at opposite sides of said conduit. One of the shafts 24 is furnished with burnishing wheels 25, partially exposed through clearances or mouths in branch leads 26 to the conduit 21 so that when the 35 wheels 25 are active upon work the dust, shavings or removed particles from footwear will be sucked through the branches 26 into the conduit 21, this suction being set up by the fan 19 driven from the motor unit 15. The course of the dust, shavings or removed matter is through the housing or casing 20, the nipple 21' and into the casing 19. Discharge of the contents of the casing 19 is had through a discharge spout 27 for depository in a suitable receiver.

Fitted on the shaft 21 are belt wheels 28 having trained thereover endless belts 29, these being trained over companion pulleys 30 fitted to the driving shaft 16 of the motor unit 15. The shafts 24 are driven from this motor unit. However, on 45 rotation of the turret to bring the tools into convenient position for use, those tools or a tool next to the operator of the machine will become active while those remote will be rendered inactive. This is brought about through the eccentric 50 14 which slackens these belts common thereto. The pulleys 28, 29 and 30 are confined within the guards or shields 31, these being of extensible kind and such as to operate on the belts 29 when 55 slackened so as to cause the latter to leave the clutches of the pulleys 28, 29 and 30 and in this way those tools not to be active will become positively passive. The shields 31 also eliminate the 60 possibility of an operator coming in contact with the driving and driven connections during the operation of the machine. The end heads 23 of the 65 turret at suitable intervals concentric to the conduit 21 are joined together by tie rods 32. The turret is freely rotatable as before set forth.

Carried by the end head 23 of the turret is a 70 bracket 33 having journaled therein spaced parallel rotatable operable stems 34 and 35 respectively, one being for a heel trimming tool and the other for a sole trimming tool hereinafter fully described.

The stems 34 and 35 carry belt pulleys 36 over

which are trained endless belts 37. The belt pulleys 36 and the belts 37 are enclosed in a guard or shield 39 which functions similar to the guards or shields hereinbefore set forth. Each stem 34 or 35 has fixed thereto a circular cutter 40 formed with horizontally arranged radially disposed cutting blades 41, these being uniformly spaced from each other. The cutter 40 operates within a gauge cap 42 internally threaded for adjustable engagement with an annular rim 43 at 10 the outer open end of a cylinder 44 being telescopically fitted over a tubular base extension 45 which is fixed at 46 to the bracket 33. The stem 34 or 35 is centered within the cylinder 44 and extension 45. The cap 42 is sustained in an 15 adjusted position by a lock nut 48 fitting the cylinder 44 being threaded thereon. The cap 42 has formed therein the arcuate shaped openings 49 and 50 respectively. The opening 49 allows for the introduction of work such as a sole or 20 heel of a shoe or other footwear to the cutter 40 while the opening 50 functions as a dischargeway for trimmings made by the cutter 40. This cap 42 supports an adjustable gauge member 51 being adjustable at 52 for regulating the trimming operation in the use of the sole or heel trimming tool. The sole trimming tool is denoted at 53 while the heel trimming tool is denoted at 54, respectively. The cylinder 44 is adjustable on the tubular extension 45 to regulate the action 30 of the cutter 40 in the operation thereof.

On certain of the shafts 24 is fitted a sanding wheel or disc involving the disc body 55 carrying at its periphery a sanding tape or strip 56, the ends 57 thereof being held fast by clamping rollers 58, these being adjustably fitted within the wheel or disc 55 adjacent to the periphery thereof. Such tape or strip 56 is trained about the periphery of the said body 55 and the rollers 58 clamp the ends of this strip or tape as is clearly shown in Figures 11 and 12 of the drawings. The rollers are held adjustable by friction latches 59 built within the body 55. These rollers 58 are held against lateral displacement by retaining screws 60 engageable in annular channels 61 provided in said rollers. The rollers 58 maintain the tape or strip 56 tight peripherally about the body 55 and such strip or tape is employed for grinding or finishing purposes to the work.

The cylinder 44 is held adjustable upon the extension 45 by a set screw 62 engaged in the said cylinder 44 and binding against the extension 45. By adjustment of the cylinder 44 the cap 42 can be moved toward or away from the cutter 40 with respect to its blades 41. This cutter 40 is 55 detachably secured to the stem 34 as at 63 for replacement purposes or for substituting other cutters or new ones.

On the bearing 13 is built a latch 64 which is engageable with the end head 23 next thereto and in this manner the turret is held in its 60 adjusted position to eliminate accidental turning thereof, the turret being manually adjusted and the latch 64 is hand controlled.

Each of the shields 31 and also the shield 39 involves the outer extensible sections 65 and 66 respectively, these being telescopically fitted so that the same shift with a change of the position of the pulleys 28, 29 and 30 through eccentric activity of the turret, these shields being 70 of skeleton form and are provided with side cheeks which fit about the shafts 16, 24, 34 and 35, respectively.

In Figures 13 to 16 inclusive of the drawings there is shown a modification of the invention 75

wherein the driving shaft 66 of the motor or power unit is centered with relation to the turret, a portion thereof being indicated at 67 and this shaft 66 carries a plurality of belt pulleys 68 over which are trained the endless belts 69 and 70 respectively. The belt 70 passes over pulleys 71 fixed to the driven shafts 72 for the sole and heel trimmers hereinbefore described. The belts 69 are trained over pulleys 73 fixed to the shafts 74 journaled in the turret 67 concentric to the driving shaft 66 which is the axis for the said turret.

Fitting the tie rods 75 for the turret 67 are rocking belt tighteners 76 and 77 respectively all being fitted with belt engaging rollers 78 for contact with the companion belts 69 and 70. The power unit 79 which is stationary and is located centrally with relation to the end head 80 of the turret 67 has built exteriorly thereon a cam 81 which operates upon adjustable heel screws 82 fitting the belt tighteners 76 so that a determined tightener will be operated upon by the cam 81 to tighten the belt common to this tightener so that such belt will be effective for operating a selected tool supported by the turret 67 while the other belts for operating the other tools on the turret will remain slackened and those tools rendered inactive. By adjustment of the screws 82 the tightening effect of the belt tightener 76 can be regulated and in Figure 14 of the drawings one of the belt tighteners is in position for the tightening of one of the belts while the remaining belt tighteners are inactive against the other belts so that but one tool of the turret will operate while the other tools of said turret remain passive or inactive.

The arrangement and set up of the belt tighteners operates for the same purpose as does the eccentric 14 yet it is not required that the turret 67 have eccentric access with respect to the driving shaft 66 of the power unit 79 as is required in the use of the eccentric 14 hereinbefore set forth.

It is of course understood that the structure herein described and illustrated in the drawings constituting the present invention is applicable to other types of machinery where it is desired to have one or several shafts active through selectivity and other shafts in the set up rendered inactive, therefore the present invention is not to be construed as restricted to the specific type of machine hereinbefore described.

What is claimed is:

1. A machine of the kind described comprising a rotatable turret having end heads spaced from each other and turnable on a horizontal axis, driven shafts arranged peripherally of said heads and selectively operated, work tools operated by said driven shafts, a driving element located at one end of said turret and having a driving shaft, a plurality of pulleys fixed to the driving shaft and of varying sizes with respect to each other, belt connections between the said pulleys and the driven shaft, means correlated to the belt connections for tightening and slackening the same selectively on the said pulleys, and means for variably locating the first-named means.

2. A machine of the kind described comprising a rotatable turret having end heads spaced from each other and turnable on a horizontal axis, driven shafts arranged peripherally of said heads and selectively operated, work tools operated by said driven shafts, a driving element located at one end of said turret and having a

driving shaft, a plurality of pulleys fixed to the driving shaft and of varying sizes with respect to each other, belt connections between the said pulleys and the driven shaft, means correlated to the belt connection for tightening and slackening the same selectively on the said pulleys, means for variably locating the first-named means, and a suction conduit centered with respect to said turret and having mouth pieces common to certain of the work tools.

3. A machine of the kind described comprising a rotatable turret having end heads spaced from each other and turnable on a horizontal axis, driven shafts arranged peripherally of said heads and selectively operated, work tools operated by said driven shafts, a driving element located at one end of said turret and having a driving shaft, a plurality of pulleys fixed to the driving shaft and of varying sizes with respect to each other, belt connections between the said pulleys and the driven shaft, means correlated to the belt connections for tightening and slackening the same selectively on the said pulleys, means for variably locating the first-named means, a suction conduit centered with respect to said turret and having mouth pieces common to certain of the work tools, and a suction device for the said conduit and operated from the driving shaft, the conduit and mouth pieces being turnable with the said turret and unitarily built therewith.

4. A machine of the kind described comprising a rotatable turret having end heads spaced from each other and turnable on a horizontal axis, driven shafts arranged peripherally of said heads and selectively operated, work tools operated by said driven shafts, a driving element located at one end of said turret and having a driving shaft, a plurality of pulleys fixed to the driving shaft and of varying sizes with respect to each other, belt connections between the said pulleys and the driven shaft, means correlated to the belt connections for tightening and slackening the same selectively on the said pulleys, means for variably locating the first-named means, a suction conduit centered with respect to said turret and having mouth pieces common to certain of the work tools, a suction device for the said conduit and operated from the driving shaft, the conduit and mouth pieces being turnable with the said turret and unitarily built therewith, and extensible and contractible shields enclosing the said pulleys and belt connections and operative on the belt connections when slackened for causing the latter to declutch from the said pulleys.

5. A machine of the kind described comprising a rotatable turret having end heads spaced from each other and turnable on a horizontal axis, driven shafts arranged peripherally of said heads and selectively operated, work tools operated by said driven shafts, a driving element located at one end of said turret and having a driving shaft, a plurality of pulleys fixed to the driving shaft and of varying sizes with respect to each other, belt connections between the said pulleys and the driven shaft, means correlated to the belt connections for tightening and slackening the same selectively on the said pulleys, means for variably locating the first-named means, a suction conduit centered with respect to said turret and having mouth pieces common to certain of the work tools, a suction device for the said conduit and operated from the driving shaft, the conduit and mouth pieces being turnable with the said turret and unitarily built therewith, extensible

and contractible shields enclosing the said pulleys and belt connections and operative on the belt connections when slackened for causing the latter to declutch from the said pulleys, and a stand having bearings for the fitting of the end heads of said turret therewith and rotatably supporting the latter.

6. A machine of the kind described comprising a rotatable turret having end heads spaced from each other and turnable on a horizontal axis, driven shafts arranged peripherally of said heads and selectively operated, work tools operated by said driven shafts, a driving element located at one end of said turret and having a driving shaft, a plurality of pulleys fixed to the driving shaft and of varying sizes with respect to each other, belt connections between the said pulleys and the driven shaft, means correlated to the belt connections for tightening and slackening the same

selectively on the said pulleys, means for variably locating the first-named means, a suction conduit centered with respect to said turret and having mouth pieces common to certain of the work tools, a suction device for the said conduit and operated from the driving shaft, the conduit and mouth pieces being turnable with the said turret and unitarily built therewith, extensible and contractible shields enclosing the said pulleys and belt connections and operative on the belt connections when slackened for causing the latter to declutch from the said pulleys, and a stand having bearings for the fitting of the end heads of said turret therewith and rotatably supporting the latter, each shield having inner and outer 10 15 telescopically interfitted relatively movable sections.

GEORGE C. BENNETT.
